UNITED STATES PATENT OFFICE.

MOSES C. JOHNSON, OF HARTFORD, CONNECTICUT, ASSIGNOR TO THE HELIX
GEAR COMPANY, OF SAME PLACE.

DESIGN FOR A GEARING-COVER FOR VEHICLE-FRAMES.

SPECIFICATION forming part of Design No. 31,321, dated August 1, 1899:

Application filed July 5, 1899. Serial No. 722,878. Term of patent 14 years.

To all whom it may concern:

Be it known that I, MOSES C. JOHNSON, a citizen of the United States, and a resident of Hartford, in the county of Hartford and State of Connecticut, have invented a new and original Design for a Gearing-Cover for Vehicle-Frames; and I do hereby declare the following, when taken in connection with the accompanying drawings, to be a full, clear, and exact description of the same, and said drawings constitute part of this specification, and represent, in—

Figure 1, a view in side elevation of the gearing-cover; Fig. 2, a view in front elevation of the gearing-cover, and Fig. 3 a view in rear elevation of the gearing-cover.

My invention relates to a design for covers for gearing, which as a whole is a special article of manufacture and when connected to or forming part of the frame of a bicycle or like vehicle includes the crank-shaft, gearing-connecting shaft, and the rear-wheel-gear covers; and said convention consists in the configuration of the structure, as hereinafter described, and shown in the drawings.

The structure as a whole presents when viewed in side elevation an elongated body part *a*, substantially cylindrical in outline and terminating at the front and the rear ends in the short cylindrical enlargements *b c*, the lines of the central and end portions of this

part merging into each other more or less gradually. Below the part *a* and at each end are the parts *d* and *e*, which are circular in outline when viewed from the side and are short cylinders as viewed from the end, so far as the outline or configuration is concerned. The part *d* has a portion *d'* less in diameter than that part which immediately underlies the body part *a*, and it is also substantially cylindrical in outline.

When viewed from either end in line with the vertical plane of the structure, the circular ends of the main portion *a* appear in contact with the edges of short cylinders *d e*, and this forms a marked and prominent feature of the general design. The essential feature of the design, however, is the arrangement of the body part *a*, terminating in the short enlargements located above and offset from the center of the cylindrical parts *d e*.

I claim—

The design for a gearing-cover for a vehicle-frame substantially as shown and described.

In witness whereof I have signed this specification in the presence of two subscribing witnesses.

MOSES C. JOHNSON.
